UNITED STATES PATENT OFFICE.

FRED L. ARDUSER, OF PARKSTON, SOUTH DAKOTA.

HOISTING-MACHINE.

1,131,103.

Specification of Letters Patent.

Patented Mar. 9, 1915.

Application filed January 17, 1913. Serial No. 742,661.

To all whom it may concern:

Be it known that I, FRED L. ARDUSER, a citizen of the United States, residing at Parkston, in the county of Hutchinson and 5 State of South Dakota, have invented new and useful Improvements in Hoisting-Machines, of which the following is a specification.

This invention relates to hoisting machines to be used in connection with the storing of hay in a hay-mow or loft of a barn.

The primary object of the invention is to provide a hoisting or power transmitting 15 machine whereby sufficient energy or power, derived from an ordinary gasoline engine, is transmitted to suitable hoisting mechanism to enable the lifting or hoisting of hay from a wagon up into the loft or hay-20 mow, thus obviating the necessity of employing horses or other animals heretofore almost universally used.

Another object of the invention is to provide suitable mechanism in connection with 25 a machine of this character wherein the energy or power, should occasion demand, may be entirely cut off at any moment without stopping or otherwise changing the speed of the engine.

30 A further object of the invention is to provide a simple and inexpensive hoisting machine, which is durable and reliable in operation and which can be manufactured and placed upon the market at a comparatively low cost.

With the above and various other objects in view the invention consists essentially in the provision of a suitable frame, upon which is mounted a roller or reel, the power 40 or energy for operating the same being derived from any adjacent source of power such as a gasoline engine, such operation being conveniently controlled by a novel and peculiar clutch mechanism.

45 Certain other features of construction together with the combination and arrangement of the several parts as will be herein-after fully described and specifically pointed out in the appended claim must be reasonably considered in determining the advantages and novel features of this invention.

In describing my invention in detail reference will be had to the accompanying 55 drawings wherein like characters denote like

or corresponding parts throughout the several views, and in which:—

Figure 1 is a top plan view of the machine. Fig. 2 is a section on line 2—2 of Fig. 1. Fig. 3 is a detail view of the clutch 60 mechanism.

Referring now more particularly to the drawings, wherein is illustrated the preferred form of my invention the numeral 1 designates the frame of the machine, mounted upon suitable wheels 2 and provided with the usual tongue 3.

While only the hoisting machinery has been illustrated in the drawings, the same is used in connection with any suitable 70 mechanism generally employed for hoisting hay from a wagon up into the loft or hay-mow of a barn, such mechanism adapted to be controlled by a rope or cable 4 attached to a reel 5 revolvably mounted upon a shaft 75 6 journaled within brackets 7 secured to the frame of the machine. Each end of the reel 5 is provided with an annular flange, the periphery of one of which is provided with a plurality of notches 9, adapted to be engaged by a suitable pawl 10 pivoted as at 11 and controlled by a hand operated rod 12 slidably mounted as at 13 upon the frame.

A sprocket wheel 14 is mounted upon one 80 end of the shaft 6 and connected to a second sprocket 15, through the medium of a chain 16, the latter sprocket forming a part of the sliding clutch mechanism to be hereinafter fully described. The sprocket 15 is mounted upon one end of a shaft 17 journaled 90 within brackets 18 upon the frame, while the other end of the shaft is provided with a suitable pulley 19 connected to any convenient source of power such as a gasoline engine (not shown) by means of a belt 20. 95 By this arrangement it will be seen that the power for operating the reel is generated from the engine and transmitted through the medium of the mechanism just described.

The means employed for controlling the 100 operation of the reel comprises a specially constructed clutch, composed of the above mentioned sprocket 15 which is slidably mounted upon the end of the shaft 17 and provided with a collar 21 formed integral therewith. The said collar 21 has a notch 22 adapted to engage a pin 23 projecting from the shaft so that the motion of the latter will be imparted to the sprocket during such engagement between the pin and 110

notch. A spring 24 is mounted upon the end of the shaft 17 and interposed between a suitable plate or washer 25 and the outer face of the wheel 15, this arrangement normally forcing the notch into engagement with the pin.

When it is desired that the shaft 17 be turned independent of the sprocket 15, the same may be accomplished by the operation 10 of a suitable hand lever 26 pivoted as at 27 upon the frame 1 and pivotally connected as at 28 to a suitable yoke 29 adapted to straddle the collar 21 thereby sliding the sprocket according to the shifting of the 15 said lever 26.

A guide 30 through which the rope 4 extends, is pivotally mounted upon a shifting member 31 in turn loosely mounted upon a cross rod 32 carried by standards 33 of the 20 frame. During the winding or unwinding of the reel the rope will necessarily move toward one or the other end of the drum, and it is to follow such movement that the member 31 is loosely mounted upon the cross 25 rod 32. A connecting rod 34 depends from the member 31 and normally fits within the forked end 35 of a hand operated lever 36 pivoted as at 37 to the frame. By manipulating the lever 36 according to the movement 30 of the rope, the shifting of the guide 30 is permitted as desired. Any fastening element such as a chain 38 may be employed for holding the machine immovable during its operation.

35 The construction of the machine having been fully described, the operation thereof is as follows: The rope 4 is first attached to any suitable hoisting mechanism for raising the hay from the wagon to the loft or hay- 40 mow and the engine started, in which event motion is imparted to the reel, the winding or turning of which will wind the rope and cause such hoisting mechanism to operate. After raising the hay as desired the lever 26 45 is manipulated, thereby throwing out the clutch mechanism and allowing the reel to unwind independent of any operation whatsoever, such unwinding being caused by the weight of the hoisting mechanism not 50 shown. Should the weight of such mechanism prove insufficient to cause the unwinding of the reel the engine may be reversed and the clutch automatically thrown or slid by the tension of the spring 24 there- 55 by unwinding the reel in this manner. When the whole length of the rope is unnecessary for the operation of the hoisting

mechanism, the reel may be stopped at any desired point by the operation of the hand rod 12, such operation causing the pawl 10 60 to engage one of the notches 9 of the reel flange thereby limiting or stopping the turning of the reel.

From the above taken in connection with the accompanying drawings it will be seen 65 that the operation of the machine is extremely simple; that the clutch mechanism is absolutely automatic and instantaneous in operation and that the substitution of an engine in place of the animal power previously used will prove a great saving of 70 both time, labor and expense.

It is thought from the foregoing that the advantages and novel features of my device will be fully appreciated.

I desire it to be understood that I may make slight changes in the construction and in the arrangement and combination of the several parts, provided such changes fall within the scope of the subjoined claim.

Having thus fully described my invention, what I claim as new and desire to secure by Letters Patent, is:—

A hoisting machine including in combination, a wheeled supporting frame, a reel 85 mounted for rotation at one end thereof, means rotating said reel, uprights upon said supporting frame, a shaft connecting said uprights, the latter serving as a stop means, a shifting member mounted for sliding 90 movement upon said shaft, said shifting member being movable from one to the other of the said stop means, the said shaft being disposed in spaced relation to, at one side of, and above said reel, a guide member pivoted to depend from the free end of said shifting member, the element wound upon the said reel being adapted to extend through an opening in said guide, a rod depending from said shifting member at the 100 opposite end thereof from that upon which the said guide member extends, said rod being rigid therewith, an operating lever pivoted to said supporting frame and pivotally connected to said depending rod for 105 shifting said guide member during an unwinding or winding of the element upon the reels, and means actuatable to control rotation of the reel, as and for the purpose set forth.

FRED L. ARDUSER.
